UNITED STATES PATENT OFFICE.

LUDWIG M. SKARUDA, OF RIVERSIDE, ILLINOIS.

DESIGN FOR A HAIR BAND.

Application filed March 3, 1926. Serial No. 16,751. Term of patent 3½ years.

To all whom it may concern:

Be it known that I, LUDWIG M. SKARUDA, a citizen of the United States of America, residing at 66 Forbes Road, in the city of Riverside, county of Cook, and State of Illinois, have invented a new, original, and ornamental Design for a hair band, of which the following is a specification, reference being had to the accompanying drawing, forming part thereof.

The illustration is a perspective view of a hair band embodying my new and original design.

I claim:

The ornamental design for a hair band, as shown.

LUDWIG M. SKARUDA.
